STEPHEN D. LAYMAN, OF EAST ORANGE, NEW JERSEY, ASSIGNOR TO CHARLES MILLER, OF LONG ISLAND CITY, NEW YORK

SHOE TREE

Application filed May 21, 1928. Serial No. 279,405.

This invention relates to shoe trees for ladies' shoes and slippers.

Various types of shoe trees have been proposed heretofore, but these have not proven to be entirely satisfactory for the following reason. These prior art devices consist essentially of a toe portion and a heel or back portion, joined by a flexible rod, which is adapted to exert a force longitudinally of the shoe, to force the toe portion into place and to hold it there. In order to keep the cost of these devices comparatively low, only one size tree has been produced, and the variations in length of the various size shoes is taken care of by the extra length of the yieldable rod. It therefore follows that the pressure exerted between the heel and toe portions varies widely for the various lengths of shoes in which the device is used. Also when used in the smaller size shoes the yieldable rod is bent upwardly with the result that it draws the vamp of the shoe out of its normal shape.

It is therefore an object of this invention to provide a shoe tree which does not depend upon support from the heel portion of the shoe to exert the necessary tension upon the toe portion thereof.

It is a further object of this invention to provide a shoe tree which is equally efficient in its operation when used in various size shoes.

Further, it is an object of this invention to provide a shoe tree in which the tension exerted upon the toe portion may be adjusted without regard to the length of the shoe.

A further object is to provide a shoe tree which holds a shoe in proper shape without stretching the same.

It is a further object of this invention to provide a shoe tree which is cheap to construct, simple to manipulate, and which is highly efficient in its operation.

And finally, it is an object of this invention generally to improve the structure of shoe trees now known.

These and other objects of the invention will be readily apparent to those skilled in the art from the following description taken

in connection with the accompanying drawings in which:

Fig. 1 is perspective view of a device embodying the present invention.

Fig. 2 is a top plan view and Fig. 3 is a bottom plan view of the device shown in Fig. 1.

Fig. 4 is a side elevational view, one side member being cut away.

Referring in detail to the drawing, the shoe tree 10 is seen to comprise two side sections 11 and 12 shaped to the form of a shoe last and adapted to hold a shoe in its proper shape when inserted therein. A mid-section or wedge 13 is disposed intermediate of the side sections. The wedge is formed as shown with its upper portion 13^a extending above the members 11 and 12. A knob or handle 14 is carried by the upper edge of the wedge 13. The internal surfaces of the side sections 11 and 12 and the cooperating surfaces of the wedge are uni-planar whereby to obtain the proper degree of adjustment without unduly spreading any particular portions of the side sections.

The following structure is provided to maintain the parts in proper association with respect to each other:

A bolt 15 having the head 15^a is countersunk in the section 11, and passes thru a slot 16 cut in the wedge member 13, and from there into the other side section 12, where it is held by head 15^b, which is movable within a slot 12^a cut in the section 12, but from which slot it cannot be withdrawn. Plugs 11^b and 12^b may be provided in the members 11 and 12 respectively to close the slots cut in said members to permit the bolt to be fixed in place as shown. This bolt 15 holds the side sections and the wedge member in associated relation. The slot 16 cut in the wedge 13 permits relative movement of the same with respect to the side sections.

Referring now in detail to Figs. 2 and 4, the structure which permits sliding of the wedge but holds the side sections from relative rotation will be described. This is seen to comprise a first pin or plug 17 rigidly held by one side member such as 12 for ex-

ample. This pin passes thru a second slot 18 cut in the wedge and into a recess 19 cut in the other side section. A second pin 20 fixedly held by a side member such as 11, for example, extends from this side member thru the slot 18 and thus aids in guiding the wedge member in its sliding movement with respect to the side sections. A recess 21 may be cut in the other side section 12 to receive the end of the pin 20. Plugs 11^c and 12^c are employed to close the recesses formed in their respective side sections, which recesses are cut during the process of inserting the pins 20 and 17 in place as shown.

In order to help hold the tree in place when it is inserted in a shoe, the plugs 25 which may be formed of felt, rubber, or other resilient materials, are provided on the bottom of the sections 11 and 12. These plugs serve to increase the coefficient of friction between the sock lining of the shoe and the bottom of the tree. Also, due to the resilient character of these plugs, when compressed they exert a pressure substantially at right angles to the sole of the shoe, thus further retarding the movement of the tree rearwardly of the shoe.

In the use of this device it is merely necessary to place the tree in a shoe and to press the wedge forwardly until the shoe fits snugly over the tree. The tree will then remain in place until the wedge is withdrawn.

Having thus described my invention, I claim:

1. A shoe tree comprising two side sections shaped to the form of a shoe or slipper and having uni-planar surfaces, an intermediate wedge shaped section having uni-planar surfaces slidably disposed with respect to said side sections, means to hold said wedge in association with said sections and to prevent their separation, means to guide said wedge section in its sliding movement, and means to grip said wedge section, said last mentioned means extending rearwardly and upwardly of said side sections.

2. A shoe tree comprising two side sections shaped to the form of a shoe or slipper and having uni-planar surfaces, an intermediate wedge shaped member having uni-planar surfaces slidably held between said sections, means holding said side sections together in adjustable spaced relation with respect to each other and to prevent their separation, and means carried by said wedge shaped member for pushing and pulling the same.

3. A shoe tree comprising two side sections shaped to the form of a shoe or slipper and having uni-planar surfaces, an intermediate wedge shaped member having uni-planar surfaces slidably held between said sections, means holding said side sections together in spaced adjustable relation with respect to each other and to prevent their separation, means carried by one of said sections to

guide the wedge shaped member in its sliding movement, and means carried by said wedge shaped member for pushing and pulling the same.

4. A shoe tree comprising a pair of side sections shaped to conform to the portion of a shoe or slipper and having uni-planar surfaces, a wedge member having uni-planar surfaces slidably mounted between said sections, said wedge members having a portion extending rearwardly and upwardly of said sections, and means to hold said sections and said wedge member in association and to prevent their separation. 70

5. A shoe tree comprising a pair of side sections shaped to conform to the toe portion of a shoe or slipper and having uni-planar surfaces, a wedge member having uni-planar surfaces slidably mounted between said section, said wedge member having a portion 80 extending rearwardly and upwardly of said sections, a knob mounted on said last mentioned portion, whereby the wedge may be manually pushed or pulled with respect to said sections, and means to hold said sections 85 and said wedge member in association and to prevent their separation. 90

6. A shoe tree, comprising two side sections, joined together in variably spaced relation and having uni-planar internal surfaces, a wedge member having uni-planar surfaces slidably disposed between said side sections, said wedge member having a slot inclined upwardly from front to rear, and means passing through said slot and between 95 said side sections for holding said wedge member and side sections in assembled relation and for guiding the movement of said wedge member. 100
